MATERIAL LOADING AND ELEVATING
DEVICEDaniel C. Jones, Port Washington, Wis., assignor
to Kwik-Mix Company, Port Washington, Wis.,
a corporation

Application February 21, 1946, Serial No. 649,173

7 Claims. (Cl. 214—119)

1

The object of my present invention has been to produce a simple and compact form of material loading and piling boom and bucket attachment for concrete mixing machines or the like.

The attachment of my invention is designed to be readily mounted upon conventional forms of mixing machines for mixing concrete of the Portland cement class of aggregate, bituminous concrete, or other similar aggregate materials required to be mixed by agitation.

A special object of my invention has been to so design the boom and bucket attachment that the boom member is made in sections, certain of which are foldable upon a main section, or in relation to such main section, whereby when the mixing machine to which my attachment is applied is in transit, or being moved from one place to another, the upper end of the boom will be of reduced height and the lower boom section will be elevated so as not to interfere with the travel movement.

Still another object of my invention has been to design special adjustable jack braking or supporting means for the attachment including the boom, so that when the loading or piling attachment is in use the same may be supported in a stable condition to prevent liability of overturning of the machine carrying the attachment, when the loading or conveying bucket reaches a travel point at the upper end of the boom, at which time its weight and that of its contents may exert an overturning force in the event the braking or jack means were not supplied.

Other objects of my invention will appear upon consideration of the detail description afforded by the following specification, in conjunction with the accompanying drawings, in which:

Figure 1 is a side elevation of a small portable type concrete mixing machine equipped with an attachment embodying the essential features of my invention.

Figure 2 is a fragmentary view illustrating the lower section of the boom up-folded to occupy its position assumed for travel movement of the mixer, and also illustrating the jack means elevated as when not in use, for the same purpose.

Figure 3 is an end elevation of my machine as equipped with the loading attachment of my invention.

Figure 4 is a sectional view taken vertically about on the line 4—4 of Figure 3, looking in the direction of the arrows, and bringing out more clearly the bucket supporting dolly or carriage that travels lengthwise of the boom; also show-

2

ing the jack means as positioned in the lower adjustment thereof similar to Figure 1.

Figure 5 is a sectional view taken about on the line 5—5 of Figure 4, bringing out somewhat more clearly the mounting of the roller dolly or carriage in relation to the sides of the boom, which are channeled, in the channel portions of which the rollers or wheels of the dolly operate.

Figure 6 is a fragmentary vertical sectional view showing the upper portion of the boom in its operative position as when the attachment is being used for loading or material piling purposes, and illustrating further the disposition of the bucket when it has reached the upper end of the boom and as it approaches its dumping position, or its substantially dumping position.

Figure 7 is a side elevation of the mixing machine as equipped with my attachment, but illustrating the boom sections as when they are down-folded as respects the top section, and up-folded as respects the lower section, with the jacks upraised and supported in inoperative position, the parts thus disposed being located ready for travel movement of the mixer in transit from one place to another.

Figure 8 is a detail sectional view bringing out more clearly the mounting of the roller shafts on the dolly to which the loading bucket is pivoted, and the manner in which the wheels of the dolly operate in the channel sides of the boom.

Figure 9 is a detail fragmentary view, a vertical section, looking toward the inner face of one side of the boom and showing the manner of securing the upper section side parts of the boom to the side parts of the main boom section.

Figure 10 is a detail sectional view taken about on the line 10—10 of Figure 9.

Referring to Figure 1 of the drawings particularly, my machine, including the attachment means of my invention, will be seen to comprise largely the mixing machine A which will include the customary mixer usually of the rotative type, and this machine may be a Portland cement concrete mixing machine, or a bituminous concrete mixing machine, as may be desired. The machine A includes a chassis 1 and a suitable superstructure frame within which the mixer is mounted and upon which a loading skip of the conventional type, designated 2, is carried. The skip 2 is adapted to be loaded while in a downward or substantially horizontal position, with the aggregate materials to be mixed, and then will be raised by cable means 3 so as to discharge its contents into the mixing drum or mixer, the cables 3 being operated by a shaft 4 having

3

pulleys on which the cables 3 wind, a suitable cable 5 operating around the winding drum 6 being employed for the actuation of the skip, the cable 5 being connected with a hoist drum, not shown in detail. All of the above construction is generally conventional in the art, and it will be noted that the chassis or frame 1 is mounted upon wheels 7, a pair of which are carried by the chassis at the opposite ends thereof.

Describing now the boom and bucket attachment means of the present invention, it is notable that I employ a boom designated generally at 8 and comprising a main section composed of the side channels 8, suitably connected by means of T-angles or the like designated 8b, or by any other cross bracing struts 10 disposed at angles to the said main channel members 8. The channels of the main boom section members 8 face inwardly or toward each other and carry at their upper ends the top folding section channels 9 of the boom. The channels of the top section 9 are pivotally connected with the channels 8 as shown at 11 so that the top boom section may be folded inwardly and downwardly toward the mixing machine when out of use as shown in Figure 7 of the drawings. When the machine is in use and the attachment employed for hoisting the loading bucket 12 to a dumping position such as shown in Figure 6, the top channels of the upper boom section, indicated at 9, are held rigidly in place on the main boom section channels 8 by suitable bolts or securing means 13 which pass through extension plates 14, see Figure 4, on the upper ends of the channel members 8, and through the lower end portions of the channel members 9 of the top boom section.

The top boom section comprising the channels 9 carries a cross shaft 15 at its upper end, and on this cross shaft are mounted small cable winding drums designated 16 about which wind the lifting cables 17 that pass downwardly from the drums 16 and are connected in a fixed manner at their lower ends to the loading bucket 12 at opposite sides of the latter.

The shaft 15 is further operated by means of an operating cable 18 which winds and unwinds about an actuating drum 19 on the shaft 15 at one end of the latter and fixed to said shaft. The hoisting cable 18 leads from the drum 19 downwardly to the mixing machine A and is connected to a suitable hoist drum mounted on said mixing machine and carried by an extension frame structure 20 extending laterally from the chassis 1 of the mixing machine, and which frame structure supports the engine 21. The cable means 18 is operated somewhat similarly to the cable means 5 by which the skip 2 is raised and lowered. In other words, the cable 18 is wound upon its hoist drum in order to turn the shaft 15 and the winding drums 16, thereby winding up the cables 17 and causing the loading bucket 12 to travel upwardly on the boom structure comprising the main section including the channel sides 8 and the top section including the channel members 9.

The boom structure likewise comprises a lower end section adapted to fold upwardly in the manner illustrated in Figure 7, said lower boom section comprising the side channel members 22, seen best in Figure 4, the same being pivotally attached at 23 to the lower ends of the channel members 8 of the main boom section. The lower boom section including the parts 22 will gravitate to its position shown in Figure 4 with its channel portions in alignment with the channel parts 8. When the lower boom section is to be folded up

4

out of the way, it may be hoisted by hand and held in a hoisted or suspended position by means of hooks 24 engaging parts 25 on the lower boom section.

For bracing or supporting the boom attachment of my invention, I utilize a pair of jack members 25 which are supported in sleeves 26 carried by brackets 27 attached to the lower ends of the boom members 8. Holding pins 28 are adapted to pass through the sleeves 26 and openings formed in the jack members 25, whereby to hold the jack members at a fixed adjustment in operative positions as shown in Figure 4, or to hold the said jack members in an elevated position raised from the ground as shown in Figure 2. Additional openings in the jack members 25 may provide for adjustment vertically of the positions of the jack members so that their lower ends may be caused to abut with the ground adjacent to the mixing machine even though there may be uneven surfaces in the ground with which the jack members should be engaged when they are arranged in their operative positions.

The boom structure comprising the top, bottom, and main sections of channels as described, is connected with the frame structure of the mixing machine A by suitable diagonal braces 29 and 30 and substantially horizontal braces 31, said braces being best seen in Figure 1 and Figure 7.

Referring to Figure 4, the bucket 12 and its mounting means are best shown in this view. The bucket 12 has rigidly mounted under the bottom portion thereof, or on a side which may be termed the dumping bottom portion, dolly or carriage means including the means or rollers 32. These wheels or rollers 32 operate in the channel portions of the boom section of my attachment, as the bucket 12 is raised and lowered relatively to said boom structure. As will be seen in Figure 4, the upper ends of the main boom channels 8 extend slightly laterally in a direction away from the mixing machine A. Also, as seen in Figure 4, the inner sides of the channels of the lower boom section, said channels designated 22, are deflected inwardly toward the machine slightly so as to form wheel pockets to enable a slight tilting of the upper portion of the bucket inwardly toward the discharge means of the mixing machine when bucket is in its lower position for receiving materials after mixing in said machine.

Describing the operation of my invention, it is notable that the bucket 12 will be in its lowermost position, as shown in Figure 1, when it receives the mixed materials from the concrete or other mixer A. When the cables 17 are operated to elevate the bucket 12, the mode of attachment of the cables to the bucket compels a slight outward movement of the bucket to cause the wheels 32 to travel from the pocket 22a of the lower boom section channels 22, against the rear or outer flanges of said channels, and thereupon continued upward movement of the bucket 12 causes the wheels 32 to travel in the channels of the main boom section 8. When the bucket 12 reaches the upper end of its movement on the main boom section, the upper rollers 32 move into the laterally extending pocket portions 8a of the channels 8 as previously referred to, see Figure 6, and thus carry the dumping bottom or side of the bucket 12 slightly laterally preliminary to its final dumping movement compelled by the raising of the bucket bodily by a pivotal movement of the connecting bracket 34 which con-

nects the upper end portion of the bucket pivotally to the upper cross shaft of the upper wheel 32 of the dolly or carriage 35. In other words, the bucket, before it reaches the upper end of the boom, has its dumping bottom or side portion parallel with the frame structure of the carriage 35, and the lower portion of the bucket rests on the rest channel 36 seen best in Figure 6. Then when the bucket reaches the dumping position of Figure 6, it may tilt on the dolly or carriage 35 in a pivotal manner about the upper wheel shaft of the dolly as a pivotal axis.

The bucket means 12 may be utilized as a loading device for loading materials mixed in the concrete mixer A onto a truck or like vehicle for carrying off. Or, the boom and bucket attachment of my invention may be employed as a means for piling non-solidifying materials mixed in a mixer of either the Portland cement or bituminous type, in a pile which may ultimately be as high as the upper end of the boom B.

It is also contemplated that under some conditions my boom and bucket attachment may be mounted upon a different type of vehicle than a concrete mixer, and thus utilized to convey material from a containing body or receiving body of any kind to a predetermined point of discharge at an elevation.

When it is desired to move the concrete mixer or vehicle which supports my boom and bucket attachment type of loader from place to place, it is contemplated that the lower section of the boom comprising the parts 22 shall be elevated to the position shown in Figure 7, the jacks 25 correspondingly elevated to the position shown in said figure, and the top section of the boom broken down to assume the downwardly and inwardly inclined position illustrated in Figure 7 by removal of the bolts 13 disconnecting the plates 14 from the channel members 9. The above operations may be quickly performed so that the supporting machine for my loading and piling attachment may be quickly readied for travel, and, in the same manner, or reverse thereof, the boom sections and the jacks may be readied for actual use of the loading attachment with relatively little delay when the machine or supporting vehicle of the attachment reaches the place where it can be put into use.

It is contemplated that when the bucket 12 reaches the position of Figure 6, which is about at its dumping position, said bucket may strike a knock-out lever 40, see Figure 1, Figure 7 and Figure 3, which knock-out lever 40 is connected by suitable rods and levers, see parts 41 and 42, Figure 7, so as to thereby throw out the clutch means for the hoisting drum by which the cables 17 for hoisting the bucket 12 are operated. Thus, the bucket 12 will not be over-run at the upper end of the boom structure with danger or possibly damaging inertia of movement. When the clutch mentioned, see Figure 3, is thrown out, a brake will be applied in accordance with conventional practice, and the bucket 12 will be held at its upper dumping position until the operator of the machine, by use of a suitable hand lever, lowers the bucket 12 to its loading position of Figure 1.

Since clutch knock-out and brake units of the types referred to are conventional in the art and commonly used for loading skips such as the skip 2, the details of such units are not material to the invention though it is desirable that a conventional type of unit be employed.

Bolts or fastenings 43 may be used, see Figure 1,

to secure the boom section 22 in operative position for use, and removed to enable folding up of the section. Likewise, the bolts 13 are removable preliminary to folding down the top boom section 9.

Having thus described my invention, what I claim as new and desire to secure by Letters Patent of the United States, is—

1. In combination with a portable chassis, a boom and bucket structure comprising an upwardly inclined boom, a bucket including a supporting dolly arranged to travel lengthwise of the boom, means for hoisting the bucket relatively to the boom for travel movement upwardly and downwardly thereon, and frame members connecting the boom structure with the chassis for rigidly supporting the boom structure, said boom structure comprising a main section, and top and bottom sections foldable downwardly and upwardly, respectively, in directions toward each other reducing the length of the boom structure for travel purposes.

2. In combination with a portable chassis, a boom and bucket structure comprising an upwardly inclined boom, a bucket including a supporting dolly arranged to travel lengthwise of the boom, means for hoisting the bucket relatively to the boom for travel movement upwardly and downwardly thereon, and frame members connecting the boom structure with the chassis for rigidly supporting the boom structure, said boom structure comprising a main or body section, a top section alignable with the main or body section and downwardly foldable upon the latter, means for holding the top section in alignment with the body or main section of the boom, a lower boom section at the lower end of the main boom section and movable relatively thereto, and means for holding the lower boom section raised when not in use.

3. The combination of parts as set forth in claim 2, in which the lower boom section is gravitatable to a position in alignment with the main boom section, and jacks carried by the main boom section, with adjusting means for the jacks to adjust them relatively to the ground level and hold the same at such adjustment.

4. In combination with a support, a boom and bucket structure comprising an upwardly inclined boom, a bucket including a supporting dolly arranged to travel lengthwise of the boom, means for hoisting the bucket relatively to the boom for travel movement upwardly and downwardly thereon, and frame members connecting the boom structure with the support for rigidly supporting the boom structure, said boom structure comprising top and bottom sections foldable at and toward the inner side of the boom structure for reducing the length of the boom structure for travel purposes.

5. The construction claimed in claim 4, in which the hoisting means comprises power operated cable means connected to the bucket to pull the bucket upwards on the boom and tilt the bucket on its dolly as the bucket reaches the upper end of the boom, the cable actuated means being mounted on the top boom section and movable therewith for effecting hoisting of the bucket.

6. The construction claimed in claim 4, in which the hoisting means comprises power operated cable means connected to the bucket to pull the bucket upwards on the boom and tilt the bucket on its dolly as the bucket reaches the upper end of the boom, the cable actuated means

being mounted on the top boom section and movable therewith for effecting hoisting of the bucket, cable drums actuated by the cable actuated means and carried by the top section, and cables connecting the drums directly to the bucket.

7. In combination with a support, a boom and bucket structure comprising an upwardly inclined boom, a chute on the support to discharge material, a bucket including a supporting dolly arranged to travel lengthwise of the boom, means for hoisting the bucket relatively to the boom for travel movement upwardly and downwardly thereon, and frame members connecting the boom structure with the support for rigidly supporting the boom structure, said boom structure comprising sections foldable one in relation to the other for reducing the length of the boom structure for travel purposes, the lower boom section having lateral pockets at its lower end extending in the direction of the support for guiding the dolly and bucket in a direction toward

and below the said chute at the lower limit of their travel movement relative to the boom structure.

DANIEL C. JONES.
